Primary Examiner — Katherine Glennon

(57) **CLAIM**

The ornamental design for a wristwatch, as shown and described.

DESCRIPTION

1. Wristwatch

- 1.1 is a front view of a wristwatch;
- 1.2 is a back view thereof;
- 1.3 is a top view thereof;
- 1.4 is a bottom view thereof;
- 1.5 is a left view thereof;
- 1.6 is a right view thereof;
- 1.7 is a front perspective view thereof; and
- 1.8 is a back perspective view thereof.

The broken lines shown in the reproductions illustrate portions of the wristwatch that form no part of the claimed design.
